US00D780346S

(12) **United States Design Patent** (10) Patent No.: **US D780,346 S**
 Meyers (45) Date of Patent: ** Feb. 28, 2017

(54) **SIDEWALK TILE**(71) Applicant: **TUF-TITE, INC.**, Lake Zurich, IL (US)(72) Inventor: **Theodore W. Meyers**, Barrington, IL (US)(73) Assignee: **TUF-TITE, INC.**, Lake Zurich, IL (US)(**) Term: **15 Years**(21) Appl. No.: **29/545,032**(22) Filed: **Nov. 9, 2015****Related U.S. Application Data**

(60) Division of application No. 29/479,189, filed on Jan. 13, 2014, now Pat. No. Des. 744,668, which is a division of application No. 29/459,722, filed on Jul. 2, 2013, now Pat. No. Des. 700,369, which is a division of application No. 29/439,118, filed on Dec. 6, 2012, now Pat. No. Des. 691,743, which is a continuation of application No. 13/349,309, filed on Jan. 12, 2012, now Pat. No. 8,920,066.
